George T. Pedersons

By his Attorney John B. Seifert

UNITED STATES PATENT OFFICE.

GEORGE T. PEARSONS, OF NEW YORK, N. Y.

FIRE-EXTINGUISHER.

1,320,027.

Specification of Letters Patent.

Patented Oct. 28, 1919.

Application filed December 10, 1915. Serial No. 66,027.

To all whom it may concern:

Be it known that I, GEORGE T. PEARSONS, a citizen of the United States, residing in the borough of Manhattan, in the city, 5 county, and State of New York, have invented new and useful Improvements in Fire-Extinguishers, of which the following is the specification.

This invention relates to fire extinguishers of the type in which a fire extinguishing material is ejected from a reservoir by the pressure of a gas, such gas being the reaction of the mixing of gas generating materials normally held in a separated condition 10 in a generator in the reservoir, and it is the primary object of the invention to provide a fire extinguisher which is in the nature of a unit sprinkler apparatus adapted to be removably supported in an opening in a ceiling or suspended from a suitable support. 15

The principal object of the invention is to provide an extinguisher in which the fire extinguishing material is released from a reservoir by fusible means, the fusing of 20 said means also causing the gas generating materials in the generator to mix, and utilizing the generated gas to forcibly expel the material from the reservoir.

In the drawings accompanying and forming 25 part of this specification Figure 1 is a sectional side elevation of a fire extinguisher showing an embodiment of my invention, the parts being shown in full lines in normal position and in dotted lines the position the parts will assume when the gas generating 30 materials mix; and Fig. 2 is a sectional side elevation of the lower portion of the extinguisher shown in Fig. 1, illustrating a modified means to close the outlet to the 35 reservoir.

In the embodiment of my invention illustrated in the drawing a fire extinguishing liquid which will volatilize at a heat above ordinary atmospheric temperature, say about 40 one hundred and sixty degrees, such as carbon tetrachlorid, is contained in a reservoir 6 of suitable material, said reservoir, as shown in Fig. 1, having an outlet to which a sprinkler head 7 is connected, this head 45 being connected to a pipe 8 extending into the reservoir, reversely bent as shown, and having an outwardly opening and inwardly closing valve 9 at the intake end, or this sprinkler head, as shown in Fig. 2, may be 50 in the nature of a fusible sprinkler head 7,

and by the fusing of which sprinkler head the liquid will be released from the reservoir 6. The upper end of the reservoir is in the form of a removable head or cover 18 having an opening with an annular depending collar 14 secured in or formed as an integral part of the head, and said collar having an inwardly extending flange. A cover 17 has screw threaded connection with the collar 14 of the head for a purpose to be 60 hereinafter described. To support the extinguisher in an opening in a ceiling it may be provided with a screw threaded flange or ring 10, or it may be suspended from a suitable support by hangers 11. 65

To forcibly eject the liquid from the reservoir I provide a generator having an outlet leading into the reservoir in which to generate gas, to be utilized to expel the liquid from the reservoir, said generator comprising 70 a receptacle 12 of a suitable material to contain a gas generating material, such as hydrochloric or sulfuric acid, said receptacle being supported in the reservoir by a flange 13 engaging with the inwardly extending flange of the collar 14. This receptacle has an outlet 19 leading into the reservoir having a check valve opening outwardly from and closing into the receptacle 12. 75

A second receptacle 15 of suitable material engages in the first receptacle and is suspended therein by a flange 16 engaging upon the flange 13 of the receptacle 12 to be supported by the flange of the collar 14 and adapted to be closed by the cover 17, the cover having means for the engagement of a wrench or the like to facilitate the connecting and removal of the cover. Gaskets are preferably interposed between the flange 80 of the collar 14 the flanges of the receptacles and the cover to maintain a tight joint. It will be obvious that by this construction the generator may be readily removed from the reservoir for cleaning or otherwise and permit cleaning of the reservoir and refilling the same, although the reservoir may have a filler opening, with a removable closure 6'. 85

The receptacle 15 is adapted to contain another gas generating material such as bicarbonate of soda, and to retain such material therein free from the material in the first receptacle, and also permit said material to mix with the material in the first receptacle when required, the receptacle 15 has a 90 100 105 110

movable bottom 20; that is, the bottom is adapted to move away from the receptacle and thereby permit the material therein to drop into the material in the first receptacle 5 with the resultant reaction. This bottom in the normal condition of the extinguisher is retained in a position contiguous to the receptacle by a stem 21, extending through the first receptacle and through an opening 22 10 in the reservoir to the exterior thereof, and retained in its normal position by fusible means consisting of a link or bar 23 of fusible material carried by a ring 23' having screwthreaded connection with a flange 24 on the reservoir. The stem 20 is slidably mounted in guides 25' in a tube 25 communicating at one end with the opening 22 and passing up through the receptacle 12 and into the receptacle 15; the bottom 20 of said 15 receptacle 15 has an inward extending tubular portion 26, closed at the upper end and to which a valve 27 is fixed, said valve having a stem 21 and the end of the tube 25 being constructed to constitute a seat, as at 20 28, for said valve.

In operation the reservoir is first filled with the liquid, when the receptacle 12 is placed in position in the reservoir and the acid poured into the same. The receptacle 30 15 with the bottom is then placed in position and the bottom firmly drawn to the receptacle through the fusible band 23 and its connection with the flange 24, when the bicarbonate of soda is placed in said receptacle and the cover 17 secured in place. In 35 a case of fire and the temperature reaches a predetermined degree higher than ordinary atmospheric temperature the fuse 23 is melted as well as the fuse of the sprinkler head 40 when a fusible sprinkler head is utilized. By the fusing of the band 23 the stem 21 with the connected bottom 20 will drop permitting the material in the receptacle 15 to drop and mix with the material in the receptacle 12, and the generated gases resulting 45 from the reaction of the mixing of the materials passing through the outlet 19 into the reservoir creating pressure therein and forcibly ejecting the liquid therefrom. 50 When the rod and bottom drop the valve 27 will engage with the seat 28 thereby preventing any of the gases passing out through the tube 25.

In the construction shown in Fig. 2 there 55 is connected to the outlet of the reservoir a fusible sprinkler head 7', the said head having the usual fusible means to retain a plug in the outlet. In this construction the fusible means of the head must be fused before the fire extinguishing liquid will be released from the reservoir.

Having thus described my invention I claim:

1. In a fire extinguisher, the combination 60 of a reservoir to contain fire extinguishing

liquid and having an outlet; a fusible sprinkler head connected to and closing the outlet; a generator in the reservoir having an outlet leading into the reservoir; means to normally maintain gas generating materials 70 in a separated condition therein; a support for said means extending through the generator and the reservoir to the exterior of the latter; means to carry said support and shut off communication from the generator 75 and reservoir with the exterior of the latter through the opening through which the support passes; and fusible means with which said support engages to maintain the means in the generator in position with the gas 80 generating materials in a separated condition in the generator, the fusing of said fusible means and of the sprinkler head permitting the materials in the generator to unite and generate gas, and opening the outlet of 85 the reservoir, substantially as and for the purpose specified.

2. In a fire extinguisher, the combination of a reservoir for a fire extinguishing liquid and having an outlet; a generator in said 90 reservoir having an outlet leading into the reservoir; a movable part within the generator to maintain gas generating materials in a separated condition therein; a stem connected to said movable part extending 95 through an opening in the bottom of the reservoir; and fusible means coöperating with said stem to maintain the movable part in position to retain the materials in the generator in a separated condition, the fusing of 100 said means permitting movement of said stem with the movable part and the mixing of the materials in the generator, substantially as and for the purpose specified.

3. In a fire extinguisher, the combination 105 with a reservoir for a fire extinguishing liquid and having an outlet, of a generator in the reservoir comprising a receptacle for a gas generating material and having an outlet leading into the generator, a second 110 receptacle in the first receptacle having a movable bottom to retain a gas generating material therein separated from the material in the first receptacle, and a stem connected to said bottom extending through the first 115 receptacle and the reservoir to the exterior thereof; and a fusible link outside of the reservoir to support said stem and the connected bottom of the one receptacle, substantially as and for the purpose specified.

4. In a fire extinguisher, the combination with a reservoir for a fire extinguishing liquid and having an outlet, of a generator in the reservoir comprising a receptacle for a gas generating material and having an 125 outlet leading into the generator, a second receptacle in the first receptacle having a movable bottom to retain a gas generating material therein separated from the material in the first receptacle, said bottom having a 130

tubular inward projecting portion, a valve at the top of the tubular portion, a tube communicating with an opening in the reservoir and extending up through the first receptacle into the tubular portion of the bottom of the other receptacle and having a valve seat at the upper end, a stem fixed to the valve extending down through the tube to the exterior of the reservoir; and fusible means 10 exterior of the reservoir coöperating with said stem, substantially as and for the purpose specified.

5. In a fire extinguisher, the combination of a reservoir to contain fire extinguishing liquid and having an outlet; a generator in which to generate gas in the reservoir having an outlet leading into the reservoir; means to maintain gas generating materials in a separated condition in the generator; a 20 support for said means extending through the reservoir to the exterior thereof; a carrier for said support and operating to shut off communication between the generator and the exterior of the reservoir through 25 the opening for the support; and a fusible link with which the support engages to maintain said support with the means connected thereto in position with the gas gen-

erating materials in a separated condition in the generator, the fusing of said link 30 permitting the support with the connected means in the generator to move and the gas generating materials to unite and generate gas, substantially as and for the purpose specified.

35 6. In a fire extinguisher, the combination of a reservoir to contain fire extinguishing liquid and having an outlet; a generator in which to generate gas in the reservoir having an outlet leading into the reservoir; 40 means to normally maintain gas generating materials in a separated condition in the generator, having a part to extend through an opening to the exterior of the reservoir; and a fusible link with which said part ex- 45 tends to the exterior of the reservoir engages to maintain said means in position in the generator with the gas generating materials in a separated condition, the fusing of said fusible link permitting the means 50 supported thereby to move and the materials in the generator to unite and generate gas, substantially as and for the purpose specified.
